CARBURETOR

Robert F. Bracke, Chicago, Ill.

Application February 23, 1935, Serial No. 7,770

10 Claims. (Cl. 261—41)

My invention relates to carburetors and is particularly concerned with fuel-lift carburetors having two or more fuel-injecting mechanisms.

An object of my invention is to provide a carburetor having an improved idling control for the fuel-injecting means.

Another object of my invention is to provide a carburetor having a fuel chamber maintained under suction and a fuel-injecting system always effective to suck fuel from the fuel chamber and capable of idling adjustment independently of the suction existing in the fuel chamber.

Another object of my invention is to provide a carburetor having a fuel chamber maintained under suction and a fuel-injecting system always effective to suck fuel from the fuel chamber and capable of adjustment for both idling operation and part throttle operation independently of the suction existing in the fuel chamber.

20. Another object is to provide a carburetor having a fuel chamber maintained under suction and a fuel-injecting system always effective to suck fuel from the fuel chamber and provided with independent idling and part throttle adjustments, both of which are independent of the suction existing in the fuel chamber.

Another object is to provide a carburetor having a fuel chamber maintained under suction and two or more independently adjustable fuel-injecting systems supplied from the same fuel chamber.

35. Another object is to provide a carburetor having multiple fuel-injecting systems, which is simple and rugged in construction, efficient and reliable in operation, and economical to manufacture.

Other objects, advantages and capabilities of the invention will appear from the following description of preferred embodiments thereof, 40 taken in conjunction with the accompanying drawings, in which—

Figure 1 is a vertical section through a down-draft carburetor embodying my invention, the same being taken on the line 1—1 of Figure 2;

45. Fig. 1a is a diagrammatic view of the carburetor shown in Fig. 1;

Fig. 1b is a diagrammatic view of a detail taken on line 1b—1b of Fig. 1a;

Figure 2 is a fragmentary sectional view, taken 50 on the line 2—2 of Figure 1;

Figure 3 is a sectional view, taken on the line 3—3 of Figure 1;

Figure 4 is a sectional plan view, taken on the line 4—4 of Figure 1, the throttle shaft and economizing mechanism being omitted;

Figure 5 is a sectional detail view, taken on the line 5—5 of Figure 2;

Figure 6 is a sectional elevational view, taken through a modified form of down-draft carburetor embodying my invention;

Figure 7 is a fragmentary sectional view, taken on the line 7—7 of Figure 6;

Figure 8 is a sectional elevation, taken on the line 8—8 of Figure 6;

Figure 9 is a sectional elevation, taken on the line 9—9 of Figure 6;

Figure 10 is a fragmentary elevational view, taken on the line 10—10 of Figure 7, showing the relation of the choke plate and booster venturi;

Figure 11 is a sectional elevation of a variation 15 of the embodiment shown in Figures 6 to 10, inclusive; and

Figure 12 is a further sectional elevation of the variation shown in Figure 11, being taken in a plane parallel to the plane of Figure 11.

Referring to the drawings, and particularly to Figures 1 to 5, the carburetor comprises a lower casting element 10 which is provided with two mixing chambers 11 arranged in juxtaposition and separated by a wall 12. Each mixing chamber 11 is provided with a relatively large Venturi tube 13. In the lower part of each mixing chamber 11, the carburetor being a downdraft carburetor, is mounted a throttle valve 14. The throttle valves 14 are rigidly mounted on a horizontal 30 shaft 15 which has bearings in the side walls of the casting 10 and also in the partition 12. On one end of the shaft 15 is mounted an actuating arm 16, connected in the usual way to the accelerator controls. On the other end of the shaft 15 35 is rigidly mounted a short arm 17 which is pivotally connected to a link 18. The link 18 is pivotally connected to a bell crank lever 19 which is pivotally mounted on the casting 10 at 20. The purpose of the bell crank lever 19 will hereinafter 40 be more fully described. It may, however, be here noted that this lever is actuated in accordance with the movement of the throttle.

The casting 10 comprises the float bowl 21, in which is located an annular float 22. This float 45 is adapted to engage a forked lever 23 which engages a valve 24 to close same when the liquid level in the bowl is sufficiently high. The seat of the valve 24 is carried in an upper casting 25 and this seat is located at the end of a duct 26 which 50 is adapted to be supplied through pipe 27 with gasoline from the main fuel tank which is below the float bowl 21.

The casting 10 is provided with flanges 28 whereby it may be secured to the engine manifold,

which manifold comprises two openings in continuation with the throttle bores below the throttle valves 14. The castings 10 and 25 are secured together by screws 29, a suitable gasket being interposed to maintain a tight connection. The casting 25 encloses the fuel bowl 21 and carries a depending cylinder 30 which extends into the opening in the float 22, so as to permit free vertical movement of the float. Within the cylinder 30 is mounted a depending metering pin 31. The metering pin 31 is rigidly secured to a spider 32, which in turn is secured to the casting 25. The openings in the spider permit free communication between the interior of the cylinder 30 and a small chamber 33 formed in the casting 25. Two ducts 34 extend from the chamber 33 for the purpose of supplying gasoline to the jets of the carburetor.

The metering pin 31 extends freely through a metering opening 35 in the center of a piston 36. The piston 36 comprises an outer cylindrical wall 37 which works freely in the cylinder 30. Immediately inside the outer wall, the piston comprises an annular well 38 for the reception of a coil spring 39, which bears against the spider 32. The outer wall of the cylindrical well 38 is constituted by the cylindrical wall 37. The inner wall of the annular well 38 is constituted by an upwardly extending cylindrical wall 40.

The cylinder 40 is closed by a top wall 41, in which is formed the metering opening 35. The interior of the cylinder 40 is shouldered at 42, so that it may be engaged by a flange 43 on the upper end of a rod 44. The rod 44 is provided with a central bearing 45 in the float bowl 21 and its lower end rests upon a screw 46 carried on the end of the bell crank lever 19 previously referred to. The flange 43 is provided with perforations 47, which provide an area considerably larger than the metering opening 35. The rod 44 is provided with a central bore 48 which is adapted to receive the metering pin 31 as the rod 44 is moved upwardly. A duct 49 communicates with the bearing 45 of the rod 44 and with the interior of both of the throttle bores at the base of the casting 10. The high manifold vacuum is thus exerted within the bearing 45 and prevents air being drawn up past the rod 44 into the float chamber 21.

The carburetor comprises an air horn 50 through which all the air used by the carburetor is admitted. This horn may be provided with an air cleaner and silencer (not shown) of any suitable type. Inside the air horn 50 is located a valve seat 51 which provides an annular chamber 52 between it and the air horn. The outer end of the valve seat 51 is cut away around its periphery to provide openings 53 so that air may pass freely into the chamber 52. The air chamber 52 communicates with an air chamber 54 formed by means of a plate 55 mounted by screws on a ribbed formation on the outside of the casting 25.

Within the air chamber 54 are located the air supply ends of the fuel supply Venturi tubes or nozzles 56 of the carburetor. These Venturi tubes are provided with extensions 57 which terminate slightly below the throats of the large Venturi tubes 13 previously mentioned. The air chamber 54 is provided on one side with a port 58 through which air is supplied to the booster Venturi tube 59. The open end of the booster 59 is located in the same plane as the port 58 and a rotatable plate 60 is held tightly against the open ends of the venturi and port. The plate 60 is non-rotatably mounted upon the shaft 61, which shaft

has a non-round end which is received in a central opening of similar shape in the plate 60.

A housing member 62 is mounted on the plate 60 by means of a spring washer 63 and a screw 64, which screw is threaded into a central opening in the reduced non-round end of the shaft 61. The shaft 61 is provided with a bearing 65 in the casting 25 and is provided with a shoulder 66 which bears against the bearing 65 and prevents longitudinal movement of the shaft in one direction, longitudinal movement of the shaft in the opposite direction being prevented by the housing member 62. Inwardly beyond the bearing member 65, the shaft 61 carries a pin 67, the purpose of which will hereinafter appear. The end of the shaft 61 remote from the housing member 62 carries a sleeve 68 into which it partly extends. The portion of the sleeve 68 which projects beyond the shaft 61 is provided with an opening 69. The sleeve 68 is rotatably mounted in a bearing 70 in alignment with the opening 65, and the bearing 70 is provided with an opening 71. The openings 69 and 71 come into register at a certain position of the shaft 61.

The opening 71 opens into the secondary air supply chamber 72 and when the openings 69 and 71 are in register, which occurs when the carburetor is choked, the secondary air supply chamber 72 is put into communication with a duct 73 in the casting 25 and a duct 74 in the casting 10. The duct 74 terminates in an opening 75 at the base of the casting 10, which opens into both throttle bores. In this way the throttle is bypassed or cracked for the admission of air when the carburetor is choked.

The booster 59 discharges into a passage 76 from whence it passes through a metering orifice 77 into a chamber 78. From the chamber 78 the air from the booster passes into an annular chamber 79, then through a port 80 into a duct 81. The end of the duct 81 turns downwardly, as shown in Fig. 1, and discharges into the secondary air chamber 2 near the upper ends of the mixing chambers 10 at a point immediately above the partition 12. It will be understood that the secondary air chamber 72 extends across the upper ends of the two mixing chambers 10, as best shown in Fig. 3. The ports 76 and 80 open to one face of the casting 25, which face is closed by a cover plate 82.

Integral with the cover plate 82 is a cage-like structure 83 which projects into a cylinder 84 in alignment with the air horn 50. The cage-like structure 83 comprises the chamber 78 around which is arranged the annular chamber 79, both previously referred to. The central chamber 78 receives an insert 85 in which is provided the metering orifice 77. The cage-like structure 83 is provided with an opening 86 to provide for communication between the duct 76 and the metering orifice 77. The cage-like structure 83 comprises an inner wall 87 which has a relatively tight fit in the cylinder 84. Inwardly of this wall the cage-like structure 83 is provided with a nipple 88.

The air valve 89 has an exterior of general convexed or mushroom shape. This valve in closed condition provides a small peripheral opening 90 for the admission of a small amount of air into the secondary chamber 72. As the valve is drawn inwardly, the conical shape of the valve seat 51 causes the clearance between the valve and its seat to increase, thereby admitting more and more air into the secondary air chamber 72.

The valve 89 is mounted on a rod 91 for free

sliding motion in a bearing 92 carried by the casting 25. The valve is pressed outwardly to closed position by means of a spring 93, which is protected against the heat of backfires by means of a telescopic housing 94. One end of the housing 94 bears against the inner side of the valve 89. The other end of the housing 94 bears against forked arms 95 which are freely mounted upon the shaft 61. The arms 95 are connected together by means of a bridge piece 96. As best seen in Fig. 1, when the shaft 61 is turned through a certain angle, which is done by the ordinary choking manipulation of the plate 60, the pin 67 engages the bridge piece 96. Subsequent movement in the choking direction causes the arms 95 to compress the spring 93 so that the choking manipulation applies a greater pressure than that ordinarily exerted by the spring 93 to tend to hold the valve 89 in closed position.

The rod 91 extends into the cylinder 84 through the nipple 88 and through the metering orifice 77. The free end 97 of the rod 91 is configured to serve as a metering rod in conjunction with the metering orifice 77 for the purpose of maintaining the flow of air through the booster Venturi tube 59 substantially constant. This results in the maintenance of a substantially uniform depression or vacuum within the float bowl 21. This depression or vacuum should ordinarily amount to about fifty inches of gasoline and it is applied to the float bowl 21 by means of a duct 98 which extends through the casting 25 from the top of the float bowl 21 to an annular chamber 99 around the throat of the booster Venturi tube 59. The annular chamber 99 communicates with the Venturi tube through perforations 100.

As best seen in Fig. 5, the plate 60 comprises an arm 101 which may be actuated by a suitable control 102 so as to choke the carburetor. The plate 60 is provided with a restricted opening 103 which communicates in all its positions with the port 58 so that the air chamber 54 is in communication with the interior of the housing 62 at all times. Air passes from the interior of the housing 62 into the Venturi tube 59 by means of an opening 104 in the plate 60. As best seen in Fig. 5, the opening 104 is relatively long and of decreasing width so that as the plate 60 is rotated to choke the carburetor, the amount of air which can be supplied to the booster 59 is progressively decreased until, in fully choked condition, only a little air is being passed therethrough.

The fuel supply Venturi tubes or nozzles 56 are threadedly mounted in bores 105. Each nozzle 56 cooperates with its bore to form an annular space 106 which communicates with the interior of the throat of its nozzle by means of small ducts 107. The ducts open into the throat of their nozzle just below a step therein and supply fuel to such nozzle.

At a point further away from the throat of the Venturi tubes in the down-stream direction, each Venturi tube 56 is provided with a further annular recess 108 which communicates to the interior of its Venturi tube through small ducts 109. Each of the annular spaces 108 is in communication with a duct 110 in the casting 25, which duct registers and communicates with a duct 111 in the casting 10. The duct 111 communicates with a throttle bore at a point below the throttle valve 14 and each contains a valve seat 112 (Fig. 4). A valve 113 is arranged to cooperate with the seat 112 so that the flow through the duct system 111, 110 under all conditions can be regulated to a nicety.

Within the cylinder 84 the rod 91 rigidly carries a piston 114 which has a working fit in the cylinder. This cylinder serves as an abutment tending to hold the valve 89 in closed position under the action of the spring 93. This piston 114 cooperates with the cylinder 84 to provide a dashpot effect, which prevents the valve 89 from fluttering. The rod 91 has a free fit within the nipple 88 so that air may slowly pass from and into the cylinder 84.

The operation of the carburetor is as follows: Assuming the engine to be stopped and cold, the valve 89 being, of course, closed, then to start the engine the plate 60 is manually actuated by the rod 102 so as to limit the amount of air which passes through the opening 104 into the booster venturi 59. This same movement of the plate 60 rotates the shaft 61 and the throttle valves are by-passed through port 71, port 69, duct 73, duct 74 and opening 75. This by-passing has the same effect as opening the throttle valve slightly. The rotation of the plate 60 also compresses the spring 93 so as to apply greater closing force upon the valve 89.

During choking, a high vacuum or depression is created in the mixing chambers 11 and in the secondary air chamber thereabove. This high vacuum would cause a very heavy flow of air through the booster Venturi tube 59 which, in turn, would result in a very high depression or vacuum in the float bowl 21. Such an excessively high vacuum or depression would effectively prevent the supply of any fuel to the Venturi tubes 56. The creation of this high vacuum is prevented by the registry of a narrow part of the opening 104 with the booster Venturi tube 59. The opening 104 is conformed so that the vacuum or depression in the bowl 21 is held, during choking, at normal degree, which may, for example, be about fifty inches of gasoline.

It may here be noted that the valve 89 being held strongly towards its closed position during choking, the metering pin 97 has a very narrow portion located within the metering orifice 77 so that the orifice is substantially unrestricted during choking. At this time, owing to the substantially closed condition of the valve 89, practically all the air entering into the mixing chambers 11 is supplied through the Venturi tubes 56. These Venturi tubes receive their air from the chamber 54 which is open to atmosphere through the openings 53. Consequently, a very high degree of suction is exerted by the Venturi tubes 56 for the supply of the large amount of fuel necessary for the production of a rich starting mixture.

It is important that both Venturi tubes 56 provide exactly the same idling mixture, and an important feature of my invention lies in providing means whereby the idling operation of each Venturi tube 56 may be adjusted independently of the other. The Venturi tubes 56 are correlated with the booster Venturi tube 59 so that under normal idling conditions the Venturi tubes 56 would just be unable to overcome the depression or suction in the float bowl 21, at least to the extent of supplying a sufficiently rich mixture for normal idling of the engine.

The suction of the Venturi tubes 56 is therefore increased by suction exerted by the engine through passages 109, 108, 110 and 111. The increase of suction thus exerted may be very considerable since a high degree of vacuum or depression exists in the throttle bore below the substantially closed throttle valve 14. This increase of suction may be regulated to a nicety by 75

altering the setting of the valves 113 so that a proper idling mixture is produced. This adjustment is individual to each of the Venturi tubes 56 and, as a result, each may be adjusted independently so that perfect fuel distribution can be attained and the Venturi tubes 56 may be perfectly matched. While the adjustments which I have described are primarily concerned with the idling operation of the engine, these adjustments affect the engine operation to a progressively lesser and lesser extent as the speed of the engine increases until the speed of the engine corresponds to a vehicle speed of approximately twenty-five or thirty miles per hour, after which the effect of the idling adjustments becomes negligible.

During normal running of the engine, the valve 89 opens to a certain degree, depending upon engine speed, to admit a relatively large amount of secondary air. This movement of the valve 89 from its initial closed position, causes a movement of the metering pin 97 within the metering orifice 77. The metering pin 97 is so configured that it provides a variable restriction for the flow of air through the booster Venturi tube 59. This restriction is correlated with the depression existing in the mixing chambers 11 at various speeds, so that the vacuum or depression in the float bowl is maintained substantially constant. Whenever the throttle is opened rapidly, the rod 44 is moved upwardly and the piston 36 is moved upwardly thereby within the cylinder 30, so that an extra amount of gasoline is supplied through the ducts 34 to the venturis 56 in order that the desired acceleration of the vehicle may be quickly accomplished. Since the metering opening 35 is provided in the piston 36, no check valve is needed in this piston.

At part throttle operation, at which practically all ordinary steady driving is done, the pin 31 effectively impedes flow of gasoline through the opening 35, giving a lean mixture best suited for economical operation. During wide open throttle operation, the pin 31 permits a large amount of gasoline to pass through the opening 35, giving a rich mixture and thereby providing the high torque suitable for high acceleration or for heavy load.

It may here be noted that the improved carburetor is well adapted for touch throttle operation, that is, driving slowly with the occasional slight opening of the throttle. The smooth performance given by the present carburetor under these conditions is due to the fact that all the fuel is fed through two paths, one for each manifold. As a result, the path of the incoming fuel is always maintained in wet condition, which enables the driving operation mentioned to proceed with smoothness.

The embodiment of the invention illustrated in Figs. 6 to 10, inclusive, comprises an upper casting 115 and a lower casting 115' secured together. The lower casting 115' is mounted upon the upper end of the dual manifold 116 with the two throttle bores 117 in alignment with the two manifold inlets 118. The mixing chambers 119 are provided with relatively large Venturi tube inserts 120 and they contain throttle valves 121 mounted on a single shaft 122. At one end the shaft 122 carries a cam 123. At the other end it carries an actuating arm 124 whereby the throttles may be opened and closed.

The fuel feed Venturi tubes or nozzles 125 are located above and in alignment with the mixing chambers 119 and they are provided with

tubular extensions 126 which terminate slightly below the throat of the Venturi tubes 120. The fuel feed Venturi tubes 125 provide annular spaces 127 which communicate to the interior of the Venturi tubes near their throats through small passages 128. Two separate ducts 129 lead from the two annular spaces 127 into the upper part of chambers 130, for the supply of fuel to the Venturi tubes 125. As is best seen in Fig. 9, the Venturi tubes 125 are open to the atmosphere.

The booster Venturi tube 131 communicates with the atmosphere through an opening 132 in a plate 133. As best seen in Fig. 10, the opening 132 is relatively long and of decreasing width so that when the plate 133 is actuated by a suitable control rod 134 to choke the carburetor, a relatively narrow opening is left for the supply of air to the Venturi tube 131.

The Venturi tube 131 provides an annular space 135 which is connected by a duct 136 to the upper part of the float chamber 137. The annular space 135 is connected to the interior of the Venturi tube 131 near its throat by means of openings 138, so that the air passing through the opening 132 and the Venturi tube 131 creates a vacuum or depression within the float chamber for the elevation of fuel from the automobile tank. The Venturi tube 131 discharges into a duct 139 which is connected through a metering orifice 140 with a duct 141. The end of the duct 141 turns downwardly, as best shown in Fig. 6, and opens into the secondary air chamber 142 at a point above the two mixing chambers 119 and preferably directly between these two chambers.

The plate 133 is mounted on a shaft 143 which extends through an opening 144 in the casting through the secondary air chamber 142. At its end remote from the plate 133, the shaft 143 carries a sleeve 145 which is provided with a lateral opening 146. The sleeve 145 has a bearing in the opening 147 in the casting. When the plate 133 is moved to choking position, the opening 146 is brought into register with an opening 148, whereby free communication is established between the air chamber 142 and the interior of the sleeve 145. The interior of the sleeve 145 communicates by a duct 149 with an opening 150 which extends through the wall between the two throttle bores at the base of the carburetor.

The portion of the shaft 143 which lies within the secondary air chamber 142, has rigidly mounted thereon a sleeve 151. This sleeve 151 carries an outwardly extending rib 152.

The secondary air is controlled by a valve 153 which is similar to the valve 89 of the modification first described. This valve is of general mushroom shape and in its fully closed position its periphery is located within the restricted part of the air inlet 154. When the valve 153 is drawn inwardly by the suction of the engine, its periphery moves away from the narrowest part of the air inlet 154 and the secondary air inlet opening increases in size, depending upon the degree of suction to which the valve is subjected. The valve 153 is mounted on a shaft 155 which has a bearing 156 in the casting. The end of the shaft 155 remote from the valve 153 extends into a cylinder 157 in alignment with the air inlet 154. Within this cylinder the shaft 155 rigidly carries a piston 158 which limits the movement of the valve in the outward direction. The valve 153 is provided with a coil spring 159 which tends to force the valve 153 outwardly. The spring 159 is enclosed within a telescopic housing 160 and

one end bears against the inner face of the valve 153, the other end against a part of the housing. This housing abuts against a shoulder 161 formed in the casting 115. When the plate 133 has been rotated towards carburetor choking position a certain extent, the arm 152 engages one of the housing elements 169 and further movement in the choking direction effects a further compression of the spring 159 so that the valve 153, during choking, is held very strongly towards its most fully closed position, a position at which very little air is admitted into the secondary air chamber 142.

The metering opening 140 is located in an intermediate wall 162 of a plug 163 which is forced into the outer end of the cylinder 157 with a tight fit. The duct 139 communicates to one side of the wall 162, the duct 141 communicating with the other side and between the wall 162 and a spaced wall 164, which is also part of the plug 163. The two walls 162 and 164 are connected together by fins 165. The wall 164 contains a central opening 166 through which shaft 155 extends with a free fit. The piston 158 cooperates with the cylinder 157 and the opening 166 to constitute a dashpot which prevents fluttering of the valve 153.

The portion of the shaft 155 which cooperates with the metering opening 140 is configured so that under normal running conditions, that is, during all engine operation except with choking, the air passing through the booster venturi 131 is substantially constant. As a result of this feature, a substantially constant depression or vacuum is maintained within the float chamber 137. This depression or vacuum may suitably amount to about fifty inches of gasoline. During choking, the secondary air valve 153 is held towards its closed position by the arm 152 with a force greater than that exerted by the spring 159 in non-choking operation. Consequently, during choking a very substantial depression is created within the secondary air chamber 142 and a very strong flow of air would occur through the booster venturi 131 if the plate 133 were not adjusted. This strong flow of air would create very great depression within the float bowl 137, that is, a depression which would render the fuel supply venturi 125 incapable of taking fuel from the bowl. The configuration of the opening 132 is such that during choking the normal float bowl depression or vacuum is not exceeded, but is maintained in substantially the normal degree, for example, about fifty inches of gasoline.

It will be noted that when the opening 146 is brought into register with the opening 148, which occurs during choking, the by-pass which is thus completed between the secondary air chamber 142 and the throttle bore is effectively the same as cracking the throttle valves 121.

The cam 123 cooperates with one end of a lever 167 pivoted on the casting 115'. The other arm of the lever 167 carries an adjustable screw 168 which engages the lower end of a rod 169 which extends upwardly into the float chamber 137 through a bearing 170. The upper end of the rod 169 engages a piston 171 which is freely movable in a cylindrical portion 172 depending from the casting. The cylinder 172 terminates short of the bottom of the float bowl 137, and an annular float 173 is located in the float chamber around the cylinder 172. This float is adapted to engage a forked lever 174 pivotally mounted within the bowl 137. The lever 174 engages a valve member 175 which is adapted to control the

admission of fuel from a duct 176 which extends from the fuel tank of the vehicle.

The upper end of the piston 171 is provided with a check valve 177 so that liquid may be drawn upwardly through the piston freely, but flow in the opposite direction is prevented by the check valve. Above the piston 171 the cylinder 172 contains a coil spring 178 which bears downwardly upon a flange 179 of a hollow member 180. The hollow member 180 is provided with a central opening so that fuel may pass freely from the check valve 177 through the hollow member 180. The hollow member 180 provides a central portion projecting upwardly from the flange 179, which projecting portion is encircled by the spring 178. The check valve 177 is provided with a small opening 190 to permit the free passage of a small flow of fuel for idling.

Two metering rods 181 are secured to the upper side of the piston 171, for example, by means of enlarged heads 182 which are located beneath the flange 179, this flange having openings cut in its edge to permit the vertical portions of the rods 181 to pass therethrough. These rods extend freely through openings 183 into the chambers 130 previously referred to. The chambers 130 open to the upper side of the carburetor and are internally threaded both below and above the position at which the ducts 129 communicate with the chambers.

The metering rods 181 extend through metering orifices 184 provided in cage-like structures 185 which are threaded into the chambers 130. The cage-like structures have upward extensions 186 which are hollow, in order to accommodate the upper portions of the metering rods 181, which move with the piston 171. At their upper ends these extensions 186 are provided with kerfs whereby the cage-like structures 185 may be adjusted in position by means of a screw driver. As best seen in Fig. 8, the extensions 186 project through packing glands 187 which tightly enclose the upper ends of the chambers 130.

A sealing duct 188 is provided from the interior of the bearing 170 to an opening 189 which extends into both throttle bores adjacent the lower edge of the carburetor. This sealing duct prevents leakage of air into the float chamber along the rod 169.

Each metering rod 181 has a slightly tapered portion 190 which lies in the corresponding metering orifice 184 when the engine is idling, and by adjusting the orifice 184 up and down the idling operation of the corresponding nozzle Venturi tube 125 can be varied by varying the amount of fuel supply thereto. Just below the slightly tapered portion 190 of each metering rod 181 is a more steeply tapered portion 191 which is located in its corresponding orifice when the engine is operating at part throttle.

Since the tapered portions 190 and 191 of the metering rods are provided by the same member, any adjustment of the corresponding orifice 184 with respect to one of these tapered portions necessarily produces a corresponding adjustment of this orifice relative to the other of these tapered portions. In other words, the metering pins 181 and adjustable orifices 184 constitute a means whereby each nozzle Venturi tube may be adjusted for both idling operation and part throttle operation independently of the other nozzle Venturi tube, but the idling and part throttle adjustments for a given Venturi tube are not independent of each other. When the engine is operating at full throttle, the small

lower ends of the metering rods 181 are located in the orifice 184 so that the fuel may flow freely to the Venturi tubes 125.

The present embodiment of the invention operates in substantially the same way as the embodiment first described. It is to be noted, however, that the individual and separate control which is necessary for the satisfactory operation of the two nozzles or fuel Venturi tubes 125 is attained in a different way.

In the embodiment first described, the idling operation of the fuel feed Venturi tubes was independently controlled by independently adjusting the flow of air through each Venturi tube 15 and a common metering pin was used for varying the fuel supply to the two fuel feed Venturi tubes during part throttle operation, whereas in the present embodiment a separate metering pin is provided for each nozzle, each metering pin 20 being adjustable independently of the other and adjustably controlling the supply of fuel to its nozzle during both idling and part throttle operation.

In Figures 11 and 12 I have shown a variation 25 of the embodiment illustrated in Figures 6 to 10, inclusive. In this variation the idling control means utilized in the embodiment of Figures 6 to 10, inclusive, is eliminated, and the idling control means utilized in Figures 1 to 5, inclusive, 30 is substituted therefor.

Figure 11 corresponds generally to Figure 8 which shows a section of the second embodiment of my invention. In the present variation of that embodiment, each metering pin 200 has the 35 lower portion of its large cylindrical upper end lying in its associated orifice 201 when the engine is idling. Below the enlarged upper end of each metering pin 200 is a tapered portion 202 which regulates the supply of fuel to the associated 40 nozzle during part throttle operation of the engine. Vertical adjustment of the orifices 201 does not change the idling operation of the nozzles but only affects the part throttle operation, and in this respect the metering pins 200 differ 45 from the metering pins 181 of the preferred embodiment since the latter adjusts both the idling operation and the part throttle operation of the nozzles with which they cooperate.

The nozzles or fuel feed Venturi tubes 203 of 50 the present variation are identical with those disclosed in Figure 3. Each nozzle has a throat 204 terminating in a step just below which is located the diagonal fuel feeding passages 205 which draw fuel from the fuel chamber or float 55 chamber 206, cylinder 207 and through one of the orifices 201. Below the fuel feeding passages 205 each nozzle is provided with a series of radial ports 208 communicating with an annular chamber 209 connected to a short horizontal 60 bore 210.

The upper end of a vertical passage 211 connects with one end of each horizontal bore 210 and the lower end of each passage 211 opens into a diagonal conduit 212. Each conduit 212 65 communicates with a throttle bore at a point 213 located below the corresponding throttle valve. A separate needle valve 214 adjustably controls communication between the lower end of each conduit 212 and its corresponding throttle bore.

70 Except for the differences which I have pointed out, the variation shown in Figures 11 and 12 is substantially identical with the embodiment shown in Figures 6 to 10, inclusive. It will be noted that the structures of Figures 11 and 12 75 provide an independent idling adjustment for

each nozzle and an independent part throttle adjustment for each nozzle. Furthermore, the idling adjustment and the part throttle adjustment for the same nozzle are independent of each other.

While I have illustrated and described several embodiments of my invention, it is to be understood that my invention is not limited to the particular details shown but may assume numerous forms, and that the scope of my invention is to 10 be limited solely by the following claims.

I claim:

1. In a carburetor of the class described, the combination of a plurality of nozzles, a fuel chamber from which said nozzles are supplied, 15 a common accelerator pump for all of said nozzles, and a separate metering means for each nozzle, said pump controlling all of said metering means.

2. In a carburetor of the class described, the 20 combination of a fuel chamber, a booster Venturi tube for maintaining a suction in said chamber, a nozzle supplied from said chamber, a mixing chamber into which said nozzle discharges, a secondary air inlet for said mixing chamber, a 25 valve for said inlet, a spring tending to close said valve, choke means for restricting the inlet to said booster Venturi tube, and mechanism operated by said choke means for increasing the tension of said spring.

3. In a carburetor of the class described, the combination of a plurality of nozzles, a fuel chamber from which said nozzles are supplied, an independent idling adjustment for each nozzle, a common accelerator pump for all of said nozzles, 35 and a separate metering means for each nozzle, said pump controlling all of said metering means.

4. In a carburetor of the class described, the 40 combination of a plurality of nozzles, a fuel chamber from which said nozzles are supplied, means for maintaining a suction in said fuel chamber, a common accelerator pump for all of said nozzles, and a separate metering means for each nozzle, said pump controlling all of said 45 metering means.

5. A multiple carburetor comprising a fuel chamber, means for creating a depression therein for the elevation of fuel thereinto, a plurality of fuel feed Venturi tubes for supplying fuel to a plurality of manifolds, a throttle valve controlling the supply of mixture to each manifold, a suction passage communicating with the interior of each Venturi tube and with the throttle bore posterior of the throttle valve, for augmenting the amount of fuel supplied by said Venturi tubes, 50 a common accelerator pump for all of said nozzles, and a separate metering means for each nozzle, said pump controlling all of said metering means.

6. In a carburetor of the class described, the 60 combination of a fuel feeding venturi, a fuel chamber, means for maintaining suction therein, said means consisting of a booster venturi discharging through an orifice into the carburetor throttle bore, means to keep the flow of air 65 through said booster substantially constant regardless of variations in the air flow through said throttle bore, said means comprising an element for progressively restricting said orifice as the air flow through the carburetor throttle bore 70 becomes progressively greater, a fuel-injecting system always effective to suck fuel from said fuel chamber, means for adjusting the idling operation and part throttle operation of said fuel-injecting system independently of said fuel chamber- 75

ber suction, said means providing separate and independent adjustment for idling operation and part throttle operation.

7. In a carburetor of the class described, the combination of a fuel feeding venturi, a fuel chamber maintained under suction, a fuel-injecting system always effective to suck fuel from said fuel chamber, separate means for maintaining a suction in said fuel chamber, said means consisting of a booster venturi discharging through an orifice into the carburetor throttle bore, means to keep the flow of air through said booster substantially constant regardless of variations in the air flow through said throttle bore, said means comprising an element for progressively restricting said orifice as the air flow through the throttle bore becomes progressively greater, and means for adjusting the idling operation and part throttle operation of said fuel-injecting system independently of said fuel chamber suction, said means providing separate and independent adjustments for idling operation and part throttle operation.

8. In a carburetor of the class described, the combination of a fuel feeding venturi, a fuel chamber, means for maintaining a suction therein, said means consisting of a booster venturi discharging through an orifice into the carburetor throttle bore, means to keep the flow of air through said booster substantially constant regardless of variations in the air flow through said throttle bore, said means comprising an element

for progressively restricting said orifice as the air flow through the throttle bore becomes progressively greater, a plurality of nozzles supplied from said fuel chamber, an independent idling adjustment for each nozzle, an independent part throttle adjustment for each nozzle, the idling adjustment and part throttle adjustment for a given nozzle being independent of each other.

9. In a carburetor of the class described, the combination of a fuel feeding venturi, a fuel chamber, a pair of nozzles supplied therefrom, means for maintaining a suction in said fuel chamber, said means consisting of a booster venturi discharging through an orifice into the carburetor throttle bore, means to keep the flow of air through said booster substantially constant regardless of variations in the air flow through said throttle bore, said means comprising an element for progressively restricting said orifice as the air flow through the throttle bore becomes progressively greater, an independent idling adjustment for each nozzle, and an independent part throttle adjustment for each nozzle.

10. In a fuel-lift carburetor of the class described, the combination of a fuel chamber, means for maintaining a suction therein, a pair of nozzles supplied with fuel from said chamber, an independent idling adjustment for each nozzle, a common accelerator pump for all of said nozzles, and a separate metering means for each nozzle.

ROBERT F. BRACKE.
